UNITED STATES PATENT OFFICE

GEORGE RODRIGUES, OF CASTROVILLE, CALIFORNIA

SPRINKLER

Application filed January 31, 1928. Serial No. 250,748.

This invention relates to garden sprinklers of the type wherein the sprinkler head is revolved by the reaction of the water egressing through tangentially arranged nozzles carried by the sprinkler head.

In order to obtain a maximum range for a sprinkler nozzle, the latter must be revolved very slowly to avoid a whipping action which reduces the throw of the water and consequently reduces the area irrigated by the sprinkler.

It is the principal object of the present invention to provide a simple and inexpensive sprinkler fitted with a main nozzle very slowly rotated by secondary nozzles which are actuated by the reaction of escaping water jets.

In carrying out the invention into practice, I provide nozzles on a sprinkler head adapted to be revolved by the reaction of water jets escaping therefrom. The sprinkler head operated by the nozzles is operatively connected to what I prefer to term a main nozzle, by means of a simple gear mechanism. This gear mechanism may be run in lubricant and the gear ratio between the reaction nozzles and the main nozzle is such that the main nozzle will revolve at a greatly reduced speed relative to the reaction nozzles. The construction of the device is such that friction is minimized which aids in permitting the main nozzle to be slowly revolved.

One form which the invention may assume is exemplified in the following description and illustrated by way of example in the accompanying drawings, in which:

Fig. 1 is a view in side elevation of a sprinkler embodying the preferred form of my invention with parts thereof in section to more fully disclose its construction.

Fig. 2 is a view in plan with the cover plate and reaction nozzles removed.

Referring more particularly to the accompanying drawings, 10 indicates a trunnion

having a threaded lower end 10^a by means of which it may be connected to a pipe or conduit connected with a source of water under pressure. This trunnion 10 is tubular and is adapted to be arranged stationarily in a vertical position. At its upper end the interior diameter of the trunnion 10 is reduced to provide a bore 11, an annular shoulder 12 being disposed between the larger and smaller bores of the trunnion.

A cylindrical casing 14 is provided which is interiorly bored so that it may be rotatably mounted on the trunnion 10. The casing 14 is disposed on the trunnion between an annular shoulder 15 at the upper extremity of the trunnion and a packing member 16 arranged on the trunnion at its lower end, and secured in place by a nut 17 threaded on the threaded portion 10^a of the trunnion 10. Packing 18 is interposed between the annular projecting shoulder 15 on the trunnion and the upper end of the cylindrical housing 14, and similarly packing 19 is interposed between the lower end of the housing 14 and the packing member 16. By adjusting the nut 17, the housing 14 may be properly fitted between the shoulder 15 and the packing member 16, the packing 18 and 19 acting to prevent leakage between the bore of the housing and the exterior surface of the trunnion upon which the housing revolves.

Intermediate its ends the casing 14 is formed with an annular chamber 20 which is exteriorly of the exterior surface of the trunnion. A main nozzle 21 is threaded into the casing 14 at a point where it will communicate with this annular chamber 20. The nozzle 21 projects radially and is slightly upwardly inclined so as to project a spray of water outwardly and upwardly. At its outer end this nozzle is provided with an adjusting screw 22 to break up a stream of water discharged from the nozzle, so as to distribute the water more uniformly on the ground being irrigated.

In alignment with the annular chamber 20 in the casing 14 is a plurality of ports 23 formed through the trunnion 10, so that water entering the trunnion 10 from its bottom 5 will discharge through these ports into the annular chamber and thence through the nozzle.

I intend that the main nozzle 21 be revolved very slowly about the trunnion 10 and for this purpose I provide a pair of reaction nozzles 24 which are adapted to be rotated by the reaction of the water jets escaping therefrom. These reaction nozzles are formed with tubular portions threaded 15 at their inner ends into a T 25. This T is in turn threaded on the upper end of a tubular shaft 26 arranged coaxially of the trunnion 10. At its lower end this tubular shaft 26 is formed with an annular shoulder 27 overlying the annular shoulder 12 between the two bores of the trunnion 10. It is seen that the shaft 26 fits the smaller bore 11 of the trunnion. Between the annular shoulders 27 and 12 on the tubular shaft 26 20 and trunnion 10 is packing 28 which acts to prevent the leakage of water upwardly around the shaft 26.

Secured on the shaft 26 above the trunnion is a worm 29 which bears against the top of 30 the trunnion 10 to support the shaft 26 and the nozzles 24 in its proper vertical position relative to the trunnion. This worm 29 meshes with what I prefer to term a duplex gear 30 which is arranged with axis at right 35 angles to that of the worm. This gear 30 is rotatably supported by a bracket 31 which is clamped to the reduced upper end 32 of the trunnion 10. This duplex gear 30 is so cut that it has teeth meshing with the worm 29, 40 the angle of these teeth being equal to the angular pitch of the worm 29. The gear 30 also has a worm cut in its face to mesh with the teeth of a gear 33 which is fixed to the casing 14.

45 The action of the gear arrangement is such that rotation of the worm 29 will slowly revolve the duplex gear 30. This gear through the worm cut in its face will drive the gear 33 at a still further reduced speed. 50 As the gear 33 is fixed to the casing 14 the latter will be slowly revolved, revolving the main nozzle 21.

I intend that the gears be run in lubricant so as to minimize friction and for this purpose the upper end of the casing 14 is formed 55 with a radially projecting flange 34, the peripheral edge of which is threaded. Arranged over the gear mechanism is an inverted cup-shaped cover 35 interiorly threaded so that it may be connected to the flange 34 on the casing. At its upper end this cover 35 is formed with a gland 36 carrying packing, embracing the tubular shaft 26 to prevent lubricant from escaping.

65 It is obvious, therefore, that lubricant may

be kept in the chamber formed by the inverted cup-shaped cover 35 and the flange 34, and that friction therefore between the gears will be minimized.

In operation of the device, it is constructed 70 and assembled as shown in the drawings and the lower end of the trunnion 10 is suitably connected with a source of water under pressure and stationarily disposed in a vertical position. The water entering the interior of 75 the trunnion 10 will seek to discharge through the main nozzle 21. The spray from this nozzle will be broken up partially by the adjusting-screw 22 so that the water will be evenly distributed over the surface being irrigated.

Some of the water entering will pass upwardly through the hollow shaft 26 and discharge through the reaction nozzles 24, which are disposed horizontally or radially with respect to the vertical axis of the device. The reaction of the water discharging through these nozzles 24 will cause them to revolve and as they are fixed to the tubular shaft 26, the latter will revolve in unison with them.

As the worm gear 29 is fixed to the hollow shaft 26 it will likewise be revolved and will in turn act to rotate the duplex gear 30. As the position of this gear 30 is fixed, its rotary motion will tend to drive the gear 33 and as this latter is stationary on the casing 14, this casing will revolve very slowly, slowly revolving the main nozzle 21.

As the points between the different parts are all packed, there will be no leakage. Also, as the gears are run in lubricant, friction will be minimized.

From the foregoing it is obvious that I have provided a very simple and inexpensive device wherein the main nozzle will be revolved very slowly so that whipping action of the water will be eliminated, so that a maximum area will be irrigated by my sprinkler.

While I have shown the preferred form of my invention, it is to be understood that various changes may be made in its construction by those skilled in the art without departing from the spirit of the invention, as defined in the appended claim.

Having thus described my invention, what I claim and desire to secure by Letters Patent is:

A sprinkler comprising a stationary hollow trunnion arranged vertically and to the interior of which water may be delivered, said trunnion having ports formed therein, a casing rotatably mounted on the trunnion for rotation concentric thereto, a main nozzle carried by said casing and adapted to communicate with said ports, a tubular shaft journaled in the upper end of the trunnion and extending vertically coaxially of the trunnion, horizontally arranged reaction nozzles carried by the upper end of said tubular shaft in communication with the interior

thereof, the lower end of said shaft communicating with the interior of the trunnion, a worm secured on the tubular shaft, a gear secured to the casing, an intermediate gear in mesh with the worm and with said gear on the casing whereby rotation of the tubular shaft will revolve the casing at a relatively slower rate of speed, said casing having a portion enclosing said gears whereby they may be run in lubricant.
